UNITED STATES PATENT OFFICE

2,399,357

HEAT EXCHANGER

Charles H. Koper, Needham, Mass., assignor to
B. F. Sturtevant Company, Hyde Park, Boston,
Mass.

Application October 16, 1943, Serial No. 506,539

2 Claims. (Cl. 257—124)

This invention relates to heat exchange units and relates more particularly to circular air heaters.

Heat exchange units such as so-called unit heaters or down blast heaters comprise finned tubes through which steam or hot water is circulated, and motor driven fans which force air over the tube surfaces and into the space to be heated. Such units have been unsightly, have required more material than is necessary, have had air passages in which air turbulence occurred and were not adapted for efficient operation with propeller fans.

This invention provides a heat exchange unit which is more efficient, less expensive and has a better appearance than prior units.

A feature of this invention resides in the provision of a plurality of concentric circular finned coils into which oppositely disposed, aligned headers connect, the axes of the headers lying in a plane extending diametrically through the common center of the coils.

Another feature of the invention resides in having the coils connect into one side of one header and into the opposite side of the other header whereby when the unit is located with the axes of the headers in a horizontal plane, the coils extend at slight angles to the horizontal so that condensate will drain rapidly therefrom.

Another feature of the invention resides in supporting a fan motor at the inner ends of the two headers which have been described, whereby the motor and the fan it drives are included within the outline of the unit.

Another feature of the invention resides in providing a shroud which extends completely across the unit from the inlet to the outlet thereof, around the fan and the coils whereby the air is moved through the unit without turbulence.

Objects of the invention are to improve the appearance, utility and efficiency of heat exchange units and to decrease their cost.

The invention will now be described with reference to the drawings, of which:

Fig. 1 is an elevation view of an assembled unit embodying this invention;

Fig. 2 is a view similar to Fig. 1 but with the air deflecting shutters removed;

Fig. 3 is a sectional view along the lines 3—3 of Fig. 1;

Fig. 4 is a plan view looking downwardly upon the two sheet metal stampings which enclose the unit and which provide the air guiding shroud therein;

Fig. 5 is an enlarged detail view illustrating how

the tubes of each coil are pitched with reference to the headers for facilitating drainage of condensate;

Fig. 6 is an enlarged detail view illustrating how the shutter housing is supported from the unit, and

Fig. 7 is a view of an assembled unit mounted for vertical air discharge and illustrates how the unit may be supported and how the connecting piping is arranged.

Referring first to Figs. 2 and 3, the two aligned pipes 10 and 11 are supply and return headers respectively for the plurality of concentric circular coils 12. The supply pipe 10 is perforated at a plurality of spaced points along one of its sides, the right hand side facing Fig. 3 of the drawings. All of the coils 12 except the innermost one have corresponding perforations and are attached to the pipe 10 by brazing or welding as illustrated by Fig. 5, with the respective perforations in alignment whereby the pipe 10 may serve as a supply header for supplying steam or other fluids into the coils 12. The innermost coil 12 connects into the opposite side of the header 10.

The pipe 11 is perforated similar to pipe 10 but along the opposite side thereof, the left hand side facing Fig. 3 of the drawings. The coils 12 have corresponding perforations and are attached to the pipe 11 with the respective perforations in alignment whereby the pipe 11 serves as a return header.

It will be observed that all of the coils 12 except the inner one are pitched with respect to the common axis of the pipes 10 and 11 so that when the unit is mounted for vertical discharge as illustrated by Fig. 7, the portions of the coils 12 connected to the supply header pipe 10 will be above the portions thereof connected to the return header pipe 11 whereby the coils will readily drain their contents into the return header pipe due to the difference in head between their inlets and outlets. The inner coil 12 is not pitched and serves to drain the header 10.

The inner ends of the pipes 10 and 11 are attached to the rectangular support 14 as by brazing or welding. The electric motor 15 which drives the propeller fan 16, is mounted within the support 14 with its trunnions 17 supported by the resilient mountings 18 which preferably are of the type illustrated by the K. G. Sackett Patent No. 2,301,818 which issued Nov. 10, 1942. Air moved by the fan passes over the motor and keeps it relatively cool when the unit is used as a heater.

The outer end of the pipe 10 has the T-fitting 19 screwed thereon. The supply pipe 20 is screwed into the fitting 19 and extends at right angles to the pipe 10. The supporting hanger 21 is screwed into the fitting 19 in alignment with the pipe 10 and serves to support the unit from an overhead suspension.

The outer end of the pipe 11 has screwed thereon the T-fitting 22 which in turn, has the supply pipe 23 screwed therein at right angles to the pipe 11. The plug 24 is screwed into the fitting 22 in alignment with the pipe 11 and is removable to permit a return pipe to be connected to the fitting 22 when the unit is mounted for vertical air delivery as illustrated by Fig. 7.

The sheet metal stampings 25 and 26 enclose the assemblies described in the foregoing and are attached as by the rivets 27 to the cylindrical band 28 which extends in contact with the inner surfaces of their outer walls.

The inner walls 29 and 30 of the stampings are cylindrical and extend in alignment to form a shroud extending completely through the unit. They are perforated at 31 for receiving the inner end of the hanger 21 and are similarly perforated to receive the outer ends of the pipes 10 and 11.

The shutter housing 32 is attached to the outer portion of the stamping 26 by the straps 33 which overlap the outer ends of the portions of the housing in contact with the stamping 26 and which are attached to the stamping 26 by the bolts 34.

The shutter housing 32 has a cylindrical discharge wall 35 which is in alignment with the cylindrical walls 29 and 30 which were previously described. It will be observed that the walls 29, 30, and 35 are in alignment and form a continuous shroud enclosing the heat exchange coils and the fan and extending from air inlet to air outlet. Prior units of this type have had many cavities and breaks which have caused air turbulence resulting in noise and loss of efficiency.

The shutters 36 are mounted on the rods 37, the ends of which are rotatably mounted in the bearing clips 38 which are attached to the housing 32 by the screws 39. The shutters 36 may be individually adjusted for dampering or for deflecting the air flow as desired.

By loosening the bolts 34, the shutter housing 32 may be rotated about the stamping 26 so that the shutters 36 may be used to deflect the air discharged from the unit in many different directions.

For vertical air discharge as illustrated by Fig. 7, the unit may be mounted for vertical discharge by screwing fittings 40 having spaced lugs 41 formed thereon, onto the pipes 20 and 23; by attaching the structural beam 42 to the lugs 41, and by supporting the beam 42 centrally from the overhead support 43. The pipe 23 would have the cap 44 screwed thereon and the plug 24 would be removed from the T-fitting 22 and the pipe 45 10 would be screwed into the fitting 22 to serve as the fluid return. To permit the plug 24 to be removed and the pipe 45 substituted, the stampings 22 and 23 would have a knock-out washer 46 (see Fig. 3) in a perforation through which the plug 24 15 is to be removed.

While one embodiment of the invention has been described for the purpose of illustration, it should be understood that the invention is not limited to the exact arrangement illustrated as 20 modifications thereof may be suggested by those skilled in the art without departure from the essence of the invention.

What is claimed is:

1. In a heat exchange unit, a plurality of concentric circular coils formed from hollow heat exchange tubes, and a pair of aligned headers having a common axis extending diametrically across said coils, one of said headers being located at one side of the center of said coils and having 25 one of its sides connecting with the tube forming the outermost of said coils at one side of the center thereof, the tube forming the innermost of said coils being connected to the side of said header opposite to said one side, and the other of said headers being located at the other side of the center of said coils and, having its side opposite to said one side of said one header, connecting with said coils.

2. In a heat exchange unit, a plurality of concentric circular coils formed from circular hollow tubes, and a pair of aligned circular headers extending diametrically across said coils, said tubes at one side of the center of said unit being located on one side of one of said headers and connecting therewith at said one side thereof, and at the other side of the center of said unit being located on the opposite side of the other of said headers and connecting therewith at said opposite side thereof.
